UNITED STATES PATENT OFFICE.

HARRY O. BURNS, OF EUFAULA, ALABAMA, ASSIGNOR TO DRAPER CORPORATION, OF HOPEDALE, MASSACHUSETTS, A CORPORATION OF MAINE.

SHUTTLE-FEELER.

1,288,378.

Specification of Letters Patent. Patented Dec. 17, 1918.

Application filed September 19, 1917. Serial No. 192,203.

To all whom it may concern:

Be it known that I, HARRY O. BURNS, a citizen of the United States, residing at Eu-
faula, county of Barbour, and State of Ala-
5 bama, have invented an Improvement in
Shuttle-Feelers, of which the following de-
scription, in connection with the accompany-
ing drawings, is a specification, like char-
acters on the drawings representing like
10 parts.

The invention to be hereinafter described
relates to shuttle feelers for looms.

In filling replenishing looms, it is desir-
able that the operation of the replenishing
15 mechanism shall be permitted on a call for
replenishment only provided the shuttle has
been properly boxed and is consequently in
proper position to receive the fresh bobbin
or supply of filling. It has therefore been
20 common to provide shuttle feelers which, on
call for filling replenishment, were moved to-
ward the lay from a normal front to a rear-
ward feeling position, and, if the shuttle
had not been properly boxed, the shuttle
25 feeler would indicate that fact by contact
with the shuttle and be moved frontwardly
from its rearward feeling position, thereby
through a train of mechanism well under-
stood by those skilled in the art, suspending
30 the operation of the filling replenishing
means.

It will happen at times that the shuttle
may not enter the entire box, or the shuttle
may get trapped with a portion thereof in
35 front of the shuttle-box. In such case, when
the lay makes its forward beatup movement,
the shuttle is liable to engage the shuttle
feeler while the latter is in its normal front
position, and on farther frontward move-
40 ment of the lay, cause damage to the feeler
or parts connected therewith.

An important feature of the present in-
vention consists in means for independently
45 sustaining the shuttle feeler yieldingly in
its front position so that should the feeler
be struck by the body of the shuttle as the
lay beats up, the feeler may yield front-
wardly beyond its normal front position and
50 then be returned rearwardly to its front po-
sition again when the lay goes back.

Other features and objects of the present
invention will hereinafter more fully ap-
pear from the following description in con-
nection with the accompanying drawings

which show one good, practical form of the 55
present invention.

Figure 1 is a perspective view showing a
small portion of the lay, shuttle-box, the
shuttle feeler, and a trapped shuttle;

Fig. 2 is a sectional elevation showing a 60
loom provided with a shuttle feeler of the
present invention, the shuttle feeler being
supported in its normal front position;

Fig. 3 is a view similar to Fig. 2 showing
the feeler being struck by the trapped shut- 65
tle and displaced frontwardly thereby on
the beatup movement of the lay; and

Fig. 4 is an enlarged detail showing the
yielding feeler support.

The loom frame 1 may be of any usual 70
character and have supported theron the
parts of the filling supplying means 2 which
in the present instance of the invention, com-
prises a hopper of usual construction. Pivot-
ally mounted at 3 is the transfferer 4 for 75
transferring the filling or bobbin 5 from
the hopper to the shuttle when the shuttle
is in the box adjacent the replenishing mech-
anism. Projecting downwardly from the
sleeve of the arm 4 is the arm 6 carrying 80
at its lower portion, the pivoted dog 7 which,
by a pin 8 and slotted arm 9 is operatively
associated with the shuttle feeler 10. The
parts so far described may be of any usual
or desired construction, and being well 85
known in the art, need no further elucidation.

The lay 11 is sustained upon the usual lay
swords 12 and provided with an appropriate
shuttle-box 13 for receiving the shuttle at 90
the replenishing side of the loom. Mounted
on the loom frame is a shuttle feeler guide
14 which has an inclined slot therein, com-
mon in this class of looms, for moving the
feeler lengthwise of the lay as the feeler 95
moves toward and from the lay in order to
provide the necessary slack thread or filling
between the cloth selvage and feeler when
the latter is provided with a thread holder.

The feeler 10 is pivotally mounted at 15, 100
Fig. 2, and is provided with a shoulder 16
which, when the shuttle feeler 10 is in its
normal front position, rests upon the lateral
arm 17 of a yielding support which, in the
present instance of the invention consists of 105
a pin 18 properly sustained by a bracket 19
secured to the loom frame 1 frontwardly of
and below the feeler. In the present in-

stance of the invention the bracket 19 is provided with the lateral lugs 20 through which the pin 18 extends, and the bracket is preferably secured to the loom frame by screws or convenient securing means 21. The pin 18 has secured to it a collar 22 below the upper lug 20, and between the collar 22 and the lower lug 20 the pin is surrounded by a coil spring 23, the lower end portion of which rests upon the lug 20, the construction being such that while the pin is normally held in its raised or supporting position, it may yield under a forward impulse imparted to the top portion of the feeler and 10 permit the feeler to move forwardly of its normal front position. When the disturbing cause, such as a trapped shuttle is removed from the pressure against the upper end of the shuttle feeler, the spring 23 will yieldingly force the supporting pin 18 upwardly against the shoulder 16 of the feeler and return to its normal front position.

In order that the pin 18 may not throw the feeler too far rearwardly, the lower end portion of the pin is provided with a stop 24.

From the construction described, it will be apparent that should the shuttle 25, Fig. 1, be trapped outside of the shuttle-box on a beatup movement of the lay, the wall of the shuttle will strike the upper portion 26 of the feeler and by continued movement of the lay forwardly, will force the feeler farther to the front about its pivotal mounting 15, thereby depressing the yielding supporting pin 18 without causing damage or breakage either to the feeler or to parts connected therewith. On the backward movement of the lay, or the removal of the shuttle from its trapped position, the yielding supporting pin 18 will move upwardly under the tension of its actuating spring 23 and move the feeler into its normal front position.

What is claimed is:

1. In a loom, the combination of the lay and shuttle-box, a shuttle feeler mounted for movement toward and from the lay to determine if the shuttle is properly boxed, said feeler having a shouldered portion, and a yielding support mounted on the loom frame to be engaged by the shoulder of the feeler when in front position and permit the feeler to be moved forwardly by

a trapped shuttle when the feeler is in normal front position.

2. In a loom, the combination of the lay and shuttle-box, a shuttle feeler provided with a shouldered portion and mounted for movement toward and from the lay to determine if the shuttle is properly boxed, a feeler supporting pin on which the shoulder of the feeler rests to support the feeler in its normal front position, and a spring normally acting to project the pin upwardly and yieldable to permit the pin to be depressed when the feeler is forced forwardly of its normal front position by a trapped shuttle.

3. In a loom, the combination of the lay and shuttle-box, a shuttle feeler mounted for movement toward and from the lay and longitudinally thereof, a pin having a feeler supporting portion extending transversely of the feeler to support the feeler when in normal front position, a spring acting on the pin to yieldingly sustain it in feeler-supporting position and permit the pin to be displaced by the feeler when the feeler in its normal front position is struck by a trapped shuttle.

4. In a loom, the combination of the lay and shuttle-box, a shuttle feeler having a shoulder, a pin adapted to engage the shoulder of the feeler and sustain the feeler in its normal front position, a bracket in which said shuttle feeler supporting pin is movable, a spring for moving the pin yieldingly to its shuttle feeler supporting position, and a stop to limit the movement of the pin.

5. In a loom, the combination of the lay and shuttle-box, a shuttle feeler mounted for movement toward and from the lay to determine if the shuttle is properly boxed, means operatively associated with and for so moving the feeler, a yielding support for the feeler independent of the moving means and mounted on the loom frame to be engaged by the feeler when in front position and permitting movement of the feeler forwardly of its front position by a trapped shuttle.

In testimony whereof, I have signed my name to this specification.

HARRY O. BURNS.
